UNITED STATES PATENT OFFICE.

JOHN S. HARTLEY, OF LYNN, MASSACHUSETTS, ASSIGNOR TO HARTLEY CLOCK COMPANY, OF BOSTON, MASSACHUSETTS, A CORPORATION OF MASSACHUSETTS.

DESIGN FOR A CLOCK CASE.

Application filed March 2, 1922. Serial No. 983. Term of patent 3½ years.

To all whom it may concern:

Be it known that I, JOHN S. HARTLEY, a citizen of the United States, residing at Lynn, in the county of Essex and State of Massachusetts, have invented a new, original, and ornamental Design for Clock Case, of which the following is a specification, reference being had to the accompanying drawing, forming part thereof.

Fig. 1 is a front elevation of a casing embodying my design; and

Fig. 2 is a side elevation thereof.

I claim:

The ornamental design for a clock case as shown.

JOHN S. HARTLEY.
